(57) **CLAIM**

The ornamental design for a flash drive, as shown and described.

DESCRIPTION

FIG. 1 is a perspective view of a flash drive showing the petitioner's design;

FIG. 2 is a front elevational view thereof;

FIG. 3 is a rear elevational view thereof;

FIG. 4 is a right-side, elevational view thereof;

FIG. 5 is a top plan view thereof; and,

FIG. 6 is a perspective view of FIG. 1, with a pair of shields rotated and exposing a plug.

The broken lines in the drawings are directed to environment and are for illustrative purposes only, and form no part of the claimed design.

1 Claim, 6 Drawing Sheets
